UNITED STATES PATENT OFFICE.

EWALD A. RAVES, OF AUBURN, NEW YORK, ASSIGNOR TO THE AUBURN IGNITION MANUFACTURING CO., OF AUBURN, NEW YORK.

AIR-PRESSURE PUMP.

1,072,496.

Specification of Letters Patent.

Patented Sept. 9, 1913.

Application filed December 28, 1910. Serial No. 599,777.

To all whom it may concern:

Be it known that I, EWALD A. RAVES, citizen of the United States, residing at Auburn, in the county of Cayuga and State 5 of New York, have invented certain new and useful Improvements in Air-Pressure Pumps; and I do hereby declare the following to be a full, clear, and exact description of the invention, such as will enable others 10 skilled in the art to which it appertains to make and use the same.

My present invention is an improvement in the class of air pressure pumps.

The object of my invention is to produce 15 a pump of simple construction consisting of a small number of parts which parts can be easily assembled, and the individual parts of which can be removed and replaced by other than skilled workmen or machinists, 20 and further to produce a pump in which the liability to derangement from use shall be reduced to a minimum and one that shall require but little care and attention when in use and that shall be practically closed 25 against the admission of dust to the interior or working parts.

In the drawings I have illustrated my 30 said invention and my said invention is disclosed in the following description and claims.

In said drawings, Figure 1 is a view in elevation of my improved pump. Fig. 2 is a vertical sectional view of the same in like position. Fig. 3 is a top view of the holding ring. Fig. 4 is a transverse section of the pump cylinder on line 4—4, Fig. 2. Fig. 5 is a vertical sectional view of the pump piston.

In these figures of drawing, A is the pump 40 base within which is the crank chamber. This base consists of the main portion *a* in one piece having a boss *a*² at one end, the opposite end being open but in the completed pump it is closed by the second part 45 of the base *a'* composed of a single plate. The boss *a*² is here shown as provided with the bushing *a*³ forming the bearing for the driving shaft C. The bushing *a*³ may be dispensed with and the boss *a*² made to serve as 50 a bearing for the shaft. The upper side of the base is provided with an opening communicating with the crank chamber. The walls

surrounding this opening are fitted to receive the cylinder B. This cylinder is composed of a single piece having exterior flanges *b* 55 extending around it. At the bottom, the cylinder has a slightly broader flange *b'* adapted to engage the top of the walls around the opening into the crank chamber beyond which flange is a narrow extension 60 *b*² from the cylinder to closely fit within said opening. The cylinder is thus made to communicate with the crank chamber to its full extent. The cylinder is secured to the base by the holding ring D and two rods or 65 bolts D'. The upper end of the cylinder is provided with a flange *b*³ extending outwardly somewhat beyond the flanges *b* having a flat upper surface within which the top of the cylinder rises in a circular convex 70 or dome shape. The ring D is provided with two openings *d* diametrically opposed to each other and the flanges *b*³, *b*, *b'* are each recessed in alignment with the openings *d* as shown at *b*⁴ in Fig. 4. The bolts D' 75 have their lower ends firmly fixed in the top of the base A and extend upward in engagement with the recesses *b*⁴ and through the openings *d* in the ring which lies upon the flange *b*³ of the cylinder. Nuts *d'* on these 80 rods or bolts hold the ring D tightly down upon the top of the cylinder and draw the cylinder firmly down upon the pump base. The rods or bolts by preference are fitted to the recesses *b*⁴ and the cylinder is thus 85 held from all movement. The top of the cylinder is provided with an opening extending entirely through the same. This opening or at least the upper part of the same is threaded and a depending tubular 90 extension *e* of the valve casing E is screwed therein.

The valve casing is provided with inlet valve *e'* and outlet valve *e*² preferably of the type known as "ball check valves", 95 which require no lubrication.

The driving shaft C is provided inside of the crank chamber with the crank disk C' and between the crank disk and the bearing with a collar *c* of such size as to extend 100 beyond and cover the opening in which the shaft is mounted. At the outer end of the boss *a*² the shaft is provided with a collar *c'* bearing against the outer end of the boss.

This collar is secured to the shaft by a set screw c^2 preferably engaging a depression in the shaft.

The boss a^2 is provided with an opening 5 on its upper side extending through the same to the shaft C. This opening is threaded and receives a tube a^4 the top of which is ordinarily closed by a check valve a^5 . When it is desired to lubricate the shaft, 10 the valve is depressed by the tip of the oiler or by other means and the tube filled with oil. When sufficient oil has been poured into the tube the valve is released and immediately closes the tube.

15 The piston F is provided with the metallic packing rings f, f, f and is operated by the pitman G rigidly secured to a sleeve F' movably mounted on a rod or cross bar F² passing through openings in the lower 20 part of the piston. The lower end of the pitman engages a crank pin c^3 secured to the crank disk C'. The opening in the pitman is provided with a bushing g which bears against the face of the disk, and is of such 25 extent as to bring the pitman into proper alignment with the piston. The pitman may be held on the pin by a cotter g' or any other preferred means.

The closing plate a' is secured to the main 30 portion of the base by screws. This plate is, near its lower side provided with a threaded opening and a short angular pipe H has its lower end secured therein. This pipe H is provided with a stop cock h.

35 Lubricating oil is furnished to the crank chamber through the cock h. This cock is closed after a sufficient supply of oil has been put in the chamber. The crank pin and pitman are lubricated by the oil in the 40 crank chamber and the spray and oil vapor serve to lubricate the upper bearing of the pitman and the piston.

It will be seen from the foregoing description that the lubrication of all the parts 45 requiring it, is provided for and yet all of said parts are protected against the admission of dust. In case the valves should fail to work properly, the valve case can be instantly removed and another put in its place. If it is desired to remove the cylinder the nuts on the top of the bolts or rods D' are removed and the cylinder then 50 can be lifted from its place. The piston and pitman can be then removed by with- 55 drawing the cotter from the crank pin. It will also be noted that when the cylinder is removed, and slightly lifted from the base the cotter pin g' can be removed and the piston and cylinder may be moved lat- 60 erally to disengage the lower end of the pitman from the crank pin thus disconnect- 65 ing the cylinder and piston from the base without opening the base if desired, and therefore, avoiding draining from the crank chamber the contained lubricant.

While no means for actuating the driving shaft is shown or described, it is to be understood that the same is to be given motion from some moving mechanism in any usual or preferred manner.

What I claim and desire to secure by Letters Patent is:—

1. In an air pump, the combination with the hollow base, of a detachable cylinder mounted thereon and communicating therewith, a 75 crank shaft provided with a crank pin within said base, a piston in said cylinder, a pitman pivotally connected to said piston and having a bearing aperture engaging said crank pin, whereby by detaching the 80 cylinder from said base and moving it laterally said pitman may be disengaged from the crank pin.

2. In an air pump, the combination with a hollow base comprising a single casting 85 open at one side and provided with a boss at the opposite side and a closing plate for the said open base, a driving shaft mounted in said base, a crank disk within said base connected to said shaft and provided with 90 a crank pin, a cylinder formed in one piece closed at the top and open at the bottom detachably supported on said base and communicating therewith, a piston in said cylinder, a pitman pivotally connected to said 95 piston and provided at its lower end with an aperture adapted to be slipped over said crank pin, and an exterior valve casing secured to the closed end of said cylinder and provided with inlet and outlet valves. 100

3. In an air pump, the combination with a hollow base consisting of a single casting open at one side and provided with a boss at the other side, and a closing plate for the open side of said casting, a cylinder formed in one piece, open at the lower end and closed at the upper end, supported detachably on said base and communicating therewith, a piston in said cylinder, a pitman pivotally connected to said cylinder, and provided with an aperture in its lower end, a shaft mounted in said boss, a crank disk in said base provided with a crank pin engaging said aperture in the pitman, a collar interposed between the disk and the 110 inner end of the said boss for holding the crank pin in proper alignment with the axis of the cylinder, and a collar on said shaft at the outer end of said boss, an exterior valve casing communicating with the closed 115 end of the cylinder, and inlet and outlet valves in said valve casing. 120

4. In an air pump, the combination with the base comprising a casting bored out horizontally and provided with a boss in 125 axial alignment with the bore, said casting having an aperture in its upper face communicating with said bore, a closing plate for said casting, a cylinder formed in one piece, closed at its upper end and open at 130

its lower end, mounted on said base casting and communicating with the top aperture therein, vertical bolts secured to said base casting, a clamping ring engaging the 5 closed top of the cylinder and secured to said bolts, a piston in said cylinder, a pitman pivoted to said piston at its upper end and held from lateral movement with respect thereto and provided with an aperture 10 in its lower end, a driving shaft mounted in said boss, a crank disk on said shaft within said base, and provided with a crank pin extending toward said closing plate and

engaging the aperture in the lower end of the pitman, a detachable device on said pin 15 for engaging said pitman on the side toward said closing plate and an exterior valve casing communicating with the closed end of said cylinder, and provided with inlet and outlet valves.

In testimony whereof I affix my signature, in the presence of two witnesses.

EWALD A. RAVES.
